UNITED STATES PATENT OFFICE.

WILLIAM C. FISHER, OF MIDDLETOWN, CONNECTICUT, ASSIGNOR TO
THE RUSSELL MANUFACTURING COMPANY, OF MIDDLETOWN,
CONNECTICUT.

CARTRIDGE-BELT.

SPECIFICATION forming part of Letters Patent No. 764,803, dated July 12, 1904.

Application filed April 9, 1904. Serial No. 202,397. (No model.)

To all whom it may concern:

Be it known that I, WILLIAM C. FISHER, of
Middletown, in the county of Middlesex and
State of Connecticut, have invented certain
5 new and useful Improvements in Cartridge-
Belts; and I do hereby declare the following
to be a full, clear, and exact description of the
invention, such as will enable others skilled in
the art to which it appertains to make and use
10 the same.

My invention relates to an improvement in
cartridge-belts, and more particularly to the
covering for the pockets thereof, the object of
the invention being to provide a simple and
15 efficient cover which will not interfere in any
manner when raised with removal of car-
tridges from the pockets, which shall be so
constructed and connected with the belt as to
present a smooth unobstructed surface at the
20 back of the pocket, which will closely hug the
tops of the cartridges at the ends of the pockets
and prevent movement of said cartridges with-
in the pocket, and which will be securely held
against the back of the pocket throughout the
25 full depth of the latter.

With these objects in view the invention con-
sists in certain novel features of construction
and combinations and arrangements of parts,
as hereinafter set forth, and pointed out in the
30 claims.

In the accompanying drawings, Figure 1 is
a perspective view of a portion of a cartridge-
belt embodying my invention. Fig. 2 is a
35 transverse sectional view with the cover raised.
Fig. 3 is a face view, partly broken away and
the pocket-cover raised. Fig. 4 is a trans-
verse sectional view on the line $x-x$ of Fig. 2.
Fig. 5 is a transverse sectional view on the
40 line $y-y$ of Fig. 2. Fig. 6 is a face view of
the cover 3.

1 represents the body of the belt and
consists of a multiple-woven fabric having inte-
gral woven thereon stitched at the bottom,
forming pockets 2. Each pocket is provided
45 with a cover 3, also of woven fabric. The up-
per portion 4 of the cover is made somewhat
wider than the width of the pocket, so that
when said cover is folded over the top of the

50 pocket and secured to the front thereof by a
suitable fastener 5 said cover will project
slightly over the ends of the pocket and pro-
tect the end cartridges, preventing the latter
also from possible escape. The wide portion
55 4 of the cover is also made to project slightly
into the pocket to lie parallel with the ends
thereof, as shown at 6, so as to hug the end
cartridges, holding them snugly within the
pocket and preventing any rattling or other
60 movement of said cartridges. The lower nar-
row portion 7 of the cover constitutes a re-
inforcement for the back of the pocket and
extends to the bottom thereof, where it is se-
curely fastened by the stitching 8, said stitch-
65 ing serving also to secure the bottom of the
pocket to the belt. The cover is also secured
to the belt by eyelets 9 or other suitable fas-
tening devices at points near the top of the
pocket and near the lower end of the wide
70 portion of the cover.

By constructing the cover and attaching it
75 to the pocket, as above described, the car-
tridges will not only be fully protected, but
they will be held snugly in place, superfluous
stock and undue crowding of the cartridges
are avoided, the back of the pocket will be re-
inforced with a fixed portion of the cover, ob-
70 structive seams heretofore encountered with
the attachment of the cover to the inside of
the pocket will be avoided, and the lower nar-
row portion of the cover being firmly secured
80 at the bottom of the pocket it cannot become
displaced and interfere with the ready with-
drawal of cartridges from or their insertion
into the pocket.

The belt may be provided with eyelets 7 for
85 the accommodation of suspending devices and
eyelets 8 for the reception of fastening means.

My improvements are simple in construc-
tion, cheap and easy to manufacture, and ef-
fective and convenient in use.

Having fully described my invention, what
I claim as new, and desire to secure by Letters
90 Patent, is—

1. The combination with a cartridge-belt
95 having a pocket thereon, of a cover for the
pocket having an upper portion wider than

the width of the pocket, and having a lower portion secured within the bottom of the pocket, and means for securing said cover to the belt near the top of the pocket.

- 5 2. The combination with a cartridge-belt having a pocket thereon, of a cover for the pocket, said cover having an upper portion wider than the width of the pocket and a narrower lower portion lying against the inner 10 back face of the pocket and secured at its lower end at the bottom of the pocket, said wide portion of the cover extending into the

upper portion of the pocket parallel with the ends thereof, and means for securing the cover to the back of the pocket near the top of the latter. 15

In testimony whereof I have signed this specification in the presence of two subscribing witnesses.

WILLIAM C. FISHER.
